UNITED STATES PATENT OFFICE.

FRANK B. HART, OF LAFAYETTE, INDIANA.

DESIGN FOR AN ADVERTISING-SIGN.

SPECIFICATION forming part of Design No. 25,448, dated April 28, 1896.

Application filed March 2, 1896. Serial No. 581,593. Term of patent 3½ years.

To all whom it may concern:

Be it known that I, FRANK B. HART, a citizen of the United States, residing at Lafayette, in the county of Tippecanoe and State 5 of Indiana, have invented and produced a new and original Design for an Advertising-Sign; and I do hereby declare the following to be a full, clear, and exact description of the invention, such as will enable others 10 skilled in the art to which it appertains to make and use the same.

In the accompanying drawings, which represent a sign embodying my design, Figure 1 is a side elevation of a sign having my design 15 displayed thereon, and Fig. 2 is a section taken on the line 2 2 of Fig. 1 and looking to the right in said figure.

My design consists, essentially, of the representation of a man dressed in bicycle racing- 20 costume, bareheaded, and wearing a sleeveless shirt, short trousers, long stockings, and bicycle-shoes, seated upon a safety-bicycle

in the attitude of propelling the same, the figures of the man and bicycle being displayed upon a background of netting, and 25 the portions of the wheels inclosed within the rims thereof being represented as plain flat surfaces.

In Fig. 1, A represents the netting forming the background of the sign, B represents the 30 figure of the man, and C represents the bicycle.

The figure of the man and bicycle are displayed flat upon both sides of the netting of the sign, as seen in the sectional view, Fig. 2. 35

What I claim is—

The design for an advertising-sign, substantially as herein shown and described.

In testimony whereof I affix my signature in presence of two witnesses.

FRANK B. HART.
